PUNCHBOARD AMUSEMENT DEVICE

Carlton R. Schmidt and Floyd H. Dunivan,
Stockton, Calif.

Application March 23, 1946, Serial No. 656,756

5 Claims. (Cl. 273—139)

1

This invention relates in general to an improved amusement device.

In particular the invention is directed to, and it is an object to provide, a punch board of novel electro-mechanical design and function.

Another object of the invention is to provide an electro-mechanical punch board arranged so that, upon a player punching one of a predetermined number of plugs from the board, visual—as well as audible—electrically actuated signals automatically function to indicate that a prize has been won.

Another object of the invention is to provide an electro-mechanical punch board, as above, which includes a punch board of relatively cheap and conventional construction in itself, and which may be replaced when fully punched out, by a new board, without disturbing the remainder of the apparatus.

The punch board includes plugs adapted to be punched out one by one by the player, and another object of the invention is to provide selectively placed movable members in the apparatus aligned with and adapted to be moved by the punching out of a corresponding number of plugs, and whose movement actuates the signals.

A further object of the invention is to provide an electro-mechanical punch board, as above, wherein the electric actuated signals are relay-controlled, and the relays embodied in the device being of the type which require resetting once energized; there being means provided to simultaneously operate the receiver to discharge the plugs therefrom, and to reset the relays.

A further object of the invention is to provide a practical amusement device, and yet one which will be exceedingly effective for the purpose for which it is designed.

These objects are accomplished by means of such structure and relative arrangement of parts as will fully appear by a perusal of the following specification and claims.

In the drawings:

Fig. 1 is a front elevation of the device.

Fig. 2 is a transverse sectional elevation, foreshortened, illustrating the device with the parts thereof in normal position, and with the relays open.

Fig. 3 is a similar view, foreshortened to a greater extent, illustrating the position of the parts when a winning plug is punched from the

board, and after the corresponding relay has been closed.

Fig. 4 is a fragmentary rear end elevation of the relay assembly.

Fig. 5 is an enlarged view of one of the contact pins detached, and partly in section.

Fig. 6 is a diagram of the electric circuit.

Referring now more particularly to the characters of reference on the drawings, the device 10 comprises an upstanding, ornamental cabinet or case 1 which includes a front panel 2, a base 3, and a back panel 4.

The front panel 2 is formed with a substantially centrally disposed, relatively large rectangular opening 5 backed by a punch board 6, which punch board is removably and releasably supported in the case 1 by suitable means.

The punch board 6 includes a multiplicity of symmetrically spaced, horizontal bores 7 extending therethrough, and each bore 7 initially has a rolled paper plug 8 therein, with the forward end of such plug terminating short of the corresponding end of the bore.

Above the punch board 6 the front panel 2 of the case 1 is formed with a plurality of circular windows, 9, here seven in number; such windows being of vari-colored glass or equivalent material. Behind each of the windows 9 there is mounted a separate electric-light unit 10, the circuit for which will be described hereinafter.

An upstanding skeleton frame 11 is mounted in the case 1 mainly to the rear of the punch board 6, and supports a contact block 12 directly to the rear of said punch board, but in spaced relation thereto, so as to form a vertical gap 13 therebetween. The contact block 12 comprises a plurality of upstanding, equally spaced contact plates 14 facing the punch board, and dielectric spacing sheets 15 which engage between said contact plates 14 maintain the same in proper unitary relationship. The parts of the assembled contact block 12 are secured together and into the skeleton frame by means of bolts 16 which are suitably insulated away from the plates 14.

The contact block 12 is formed with a multiplicity of horizontal bores 17 extending therethrough from front to back, and said bores 17 correspond to, and are aligned with, the bores 7 in the punch board 6. The contact block 12 includes a number of contact plates 14 corresponding to the number of light units 10 plus one, with said

additional plate being the rearmost one in the block, and which rearmost plate is identified at 18.

A plurality of contact pins 19 corresponding in number to the light units 10 are provided, with each contact pin constructed in the manner shown in detail in Fig. 5. Each contact pin 19 is metallic, and includes a dielectric guide sleeve 20 fixed and extending substantially full length thereon. One set of spring contacts 21 is secured on each metallic contact pin 20 a predetermined distance from the head 22 of such pin. In the present embodiment there are seven of the contact pins 19, and in each thereof the spring contacts 21 are a like distance from the head 22 for the purpose which will hereinafter appear. Each of the seven contact pins also includes another set of spring contacts 23, with said contacts 23 a different distance from the head 22 on each pin; i. e. a distance such that when the several pins 19 are projected into the bores 17 until the contacts 21 make electrical engagement with the plate 18, the spring contacts 23 will make electrical engagement with different and corresponding ones of the plates 14. In other words, the arrangement of the spring contacts 23 on the pins 19 is such that when said pins enter the bores 17 to a given extent, as hereinafter described, said pins each close an electrical circuit between the plate 18 and different ones of the plates 14. The spring contacts 21 and 23 gain access to the plates in the contact block 12 by reason of the dielectric sleeve 20 being cut away, as shown, to permit of projection of said contacts 21 and 23 to a slight extent.

Above the contact block 12 the upstanding skeleton frame 11 supports a horizontal transverse row of relays, indicated generally at 24, and which relays are each of a type which is normally releasably latched open, but which is adapted to be unlatched and spring-closed when the coil 25 of the relay is energized. These relays, once energized, remain closed until they are manually reset to open the same. Each relay includes a three-point spring switch 26 adapted to be sprung from the open position of Fig. 2 to the closed position of Fig. 3, by a pivotally mounted, spring-actuated bar 27 of L-shape, which bar includes a pin 28 which engages beneath the lower leaf spring of the switch, and which leaf spring is extended for this purpose. The switch closing bar 27 is normally maintained against upward swinging movement under the influence of spring 29 by means of an upstanding latch arm 30 having an offset foot on its lower end cooperating with the bar 27, as shown. When latched as in Fig. 2 the arm 30 prevents the switch-closing bar 27 from rising, but upon energization of the coil 25 the latch arm 30 swings toward said coil under the magnetic influence, and releases the bar 27, whereupon the switch 26 closes.

A horizontal relay reset bar is disposed transversely in the case directly above the position occupied by the rear ends of the switch closing bars 27 in their elevated position; said relay reset bar 31 including forwardly projecting end legs 32 pivotally connected to the frame for vertical swinging movement of said relay reset bar 31, which bar is normally maintained in an elevated operative working position by a spring 33.

The relay reset bar 31 is adapted to be swung downward to cause resetting of the bars 27, and resultant relatching of the latch arms 30 by means of a cam 34 which is mounted on a shaft 35, and rotation of which shaft causes the cam 34 to function. The cam 34 can only be actuated

to reset the relays to normal open position by the attendant of the device, for the reason that the shaft 35 can only be engaged and rotated from exteriorly of the case 1 by a special key 36 which the attendant maintains in his possession.

Directly below the vertical gap 13 between the punch board 6 and the contact block 12, there is a tray or receiver 37 fixed at the rear on a cross shaft 38, and open at the front, as shown. The tray 37 is normally in a raised, non-discharging position, as shown in full lines in Figs. 2 and 3. The contents of the tray, when the same is in the above normal position, can be seen through a window 39 in the front of the case below the punch board. Directly below the window 39 the front of the case is formed with a transversely elongated slot 40 through which the contents of the tray 37 discharge when said tray is tilted from its normal full-line position, as in Fig. 3, to the dotted line position in said figure.

The tray 37 is operated as follows:

A vertical push rod 41 is attached, at its upper end, to one end of the relay reset bar 31, and thence depends downwardly to one side of the contact block 12. Below the latter the push rod 41 is formed with a bend 42 and a forwardly projecting leg 43 which pivotally connects, at its forward end, with a crank 44, on one end of the cross shaft 38 which supports the tray 37. Under the influence of the spring 33 the relay reset bar 31 is normally raised, with the consequence that the push rod 41 is in a similar position, which in turn maintains the tray 37 normally non-tilted.

However, upon downward swinging of the relay reset bar 31 the push rod 41 acts to swing the crank 44 in a direction to tip the tray 37 forwardly, whereby its contents may deliver through the slot 40.

The electrical circuit of the device is shown diagrammatically in Fig. 6, and for the purpose of clarity the wires which are included in such circuit have been omitted from all but said one figure.

A transformer 45 mounted at any suitable point in the case 1 is connected on the primary to a 110 volt circuit, and is connected on the secondary, at opposite terminals, to a lead 46 which extends to plate 18 of the contact block, and a common lead 47 which runs to one side of each of the coils 25 of the relays 24. The remaining contact plates 14 of the contact block each connect by separate leads 48 to the coils 25 of corresponding relays on the opposite side of said coils. It will thus be seen that whenever a circuit is closed between plate 18 and any one of the plates 14, the corresponding relay coil 25 will be actuated, causing closing of the switch of the relay, of which said coil forms a part.

The center contact of each of the three-point spring switches 26 is connected to a common lead 49 extending from the same terminal of the transformer as the lead 47. One of the other contact points of each three-point spring switch 26 is connected to a separate lead 50 having the corresponding light 10 interposed therein, and said leads 50 connect with a common ground wire 51. The secondary of the transformer 45 is grounded, as at 52, to complete the light circuit; the ground 52 being tapped into the secondary of the transformer at a point to give a lower voltage for the lights 10 than is required for the relays.

The remaining contact of each of the three-point spring switches 26 is connected to a lead 53 which extends to one terminal of a buzzer

54, whose other terminal is grounded at 55.

In the above circuit it will be seen that the buzzer circuit is common to all three-point switches 26, so that upon closing of any one of said switches the buzzer actuates. The lights 10, however, illuminate only when the corresponding switch 26 is closed.

The above described amusement device functions as follows:

At the outset, and before a punch board 6 is mounted in place, the contact pins 19 are inserted part way into any desired ones of the bores 17, the location of the pins being optional with the owner or attendant. The punch board 6 is then mounted in place, a number of the plugs 8 therein alining with pins 19. The heads 22 of the contact pins are then closely adjacent the back of the board or the inner ends of such plugs. In this position of the contact pins the circuit is wholly deenergized; the lights 10 are out; and the buzzer 54 is silent.

The player is provided with a hand supported plunger 56 which includes a collar 57 intermediate its ends. The player, after selecting one of the plugs 8 as being a possible winner, places the plunger 56 against the outer end of said plug and pushes inwardly until the collar 57 abuts the face of the punch board.

If the selected plug does not engage a pin 19 and thus is not a winner, such plug after being pushed from the punch board merely drops through the vertical gap 13 into the tray 37. However, if the selected plug is a winner, it engages the head 22 of the adjacent and alined contact pin 19. As such plug is pushed rearwardly out of the punch board it causes the engaged contact pin to be pushed an equal distance through the contact block 12. The length of each plug 8 is such that when it is approximately three-quarters out of the punch board the contacts 21 are in electrical engagement with the plate 18, while the contacts 23 are in electrical engagement with one of the plates 14. This causes a momentary closing of the circuit through leads 47 and 48, and thereafter such circuit is immediately broken as the plug is pushed completely out of the punch board and falls through the gap 13 into the tray 37, and at which time the contact pin has been moved to a position such that the contacts 21 and 23 no longer electrically engage any plate. This is necessary for the reason that once a pin has closed its circuit, such circuit must be broken to permit subsequent normal functioning of the device with the remaining unselected winning pins.

When a winning contact pin is pushed through the contact block 12, as above described, with a momentary closing of the circuit between leads 47 and 48, the corresponding relay, through the coil 25, is actuated or unlatched, whereupon its switch 26 closes. When this occurs the circuit for the corresponding light 10, and the circuit for the buzzer 54, are simultaneously closed, providing a visual, as well as an audible, signal to the player, indicating that the selected plug was a winner. The illuminated light 10 is of course seen through the window 9.

Windows 9 are preferably provided with numbers or other indicia thereon as indicated in Fig. 1, to denote the relative value of the prize won.

When a win occurs, as above, the attendant inserts the key 36 on the shaft 35 and rotates the same in a direction to cause the cam 34 to swing the relay reset bar 31 downwardly. Upon such downward movement of the bar 31 it resets

the relay which was actuated by the win, and at the same time, through the medium of the push rod 41, swings the tray 37 downwardly so that the winning plug 8, together with any others

5 which may be in the tray, are discharged through the slot 40. The attendant, and the player, may thus readily check up as to how many punches he has taken. The cam 34 is then turned back to starting position, whereupon 10 the relay reset bar 31 rises to its starting point, and in turn causes the tray 37 to return to its non-accessible position.

The above described operation is repeated for 15 each of the remaining controlling plugs 8 in the punch board. It should here be stated that while seven of the contact pins 19 have been specified, this number is the minimum; as many pins, of the different contact spacings, being usable as the owner may desire. In other words more than 20 seven prizes may be given out by the full punching out of the board 6 if the owner so chooses.

When the board 6 is fully punched out, it is removed, the pins 19 are reset in the starting position, and a new board 6 mounted in place.

25 From the foregoing description it will be readily seen that there has been produced such a device as substantially fulfills the objects of the invention, as set forth herein.

30 While this specification sets forth in detail the present and preferred construction of the device, still in practice such deviations therefrom may be resorted to as do not form a departure from the spirit of the invention, as defined by the 35 appended claims.

Having thus described the invention, the following is claimed as new and useful and upon which Letters Patent are desired:

1. A game apparatus comprising a punch board 40 provided with a plurality of spaced apart bores, plugs in the bores, a contact block spaced from the punch board, said contact block being provided with a plurality of bores, such bores being in substantial alinement with the bores in the 45 punch board, a normally open electrical signal circuit, such circuit including spaced electrical contact members carried by the block and exposed through the side walls of the bores in said block, sliding contact pins disposed in a selected 50 number of the bores in the contact block, each of said pins including a pair of spaced apart contact elements operable to engage between a pair of the contact elements exposed through the walls of the bores in the block as the pin slides through 55 the bore and thereby causing the signal circuit to become operative, the pins normally projecting into the space between the punch board and the contact block, and a plunger operable to be selectively projected through one of the bores in the 60 punch board to drive the plug therefrom and into the space between the punch board and the contact block, certain of the plugs as they are driven from the punch board being engageable with contact pins projecting into said space and which 65 are alined with such plugs whereby to move such pins through their respective bores in the contact block when engaged by the plugs.

2. A structure as in claim 1 in which the width of the space between the punch board and contact block is greater than the length of the plugs whereby the latter will fall downwardly by gravity as they are driven from the bores in the punch board.

3. A game apparatus comprising a contact block 75 provided with a bore, a pair of spaced apart con-

tact elements opening into the bore, a contact pin slidably mounted in the bore, such pin having a pair of spaced apart contact elements arranged to respectively engage the contact elements in the bore when the pin is moved through the bore, means exterior of the bore and selectively movable into engagement with the pin to slide it through the bore, a signal circuit which includes the contact elements which open into the bore, such circuit also including a normally open switch, a signal giving mechanism in the circuit operative when the circuit is completed by closing the switch, a spring actuated lever operable to close the switch, a latch normally engaging and holding the lever inactive whereby the switch remains open, a normally de-energized relay coil adjacent the latch, and means to energize the coil and cause it to attract and release the latch when the pin contacts engage the contacts in the bore.

4. A structure as in claim 3 including manually operated means to re-set the latch and open the switch.

5. A structure as in claim 4 in which the re-setting means includes a pivotally mounted reset bar engageable with the lever, a shaft, a cam on the shaft engageable with the bar upon turning of the shaft, and means operable to selectively turn the shaft.
